BOOK FOR MAKING GARMENT BELTS

Salvatore Guggino, New York, N. Y.

Application June 23, 1950, Serial No. 169,839

1 Claim. (Cl. 281—15)

1

This invention relates to new and useful improvements in belts, as belts for use on or to form parts of ladies' garments at the waist region of the latter; and, more particularly, the aim is to provide a novel and valuable kit whereby, with the new kit on hand, the home or amateur dressmaker may effect the aperturing of a belt, to provide the correct plurality of evenly spaced holes along the tongue end of the belt for later selective individual engagement with a buckle prong, and also, when desired, to provide near the buckle carrying end of the belt a buckle prong accommodating slot elongated in the direction of length of the belt.

According to the present invention, further, said kit includes a round hole punching die, and a book constituted by a plurality of patterns each carrying markings to indicate placements on the belt of the apertures to be made through the belt by use of the die, with the markings all alike on the several patterns, but with each pattern of a different width from that of another or the others thereby to adapt different patterns for use in connection with belts of different widths; said markings preferably being constituted as apertures cut through a pattern.

Still a further feature of the invention is that with a pattern elongated in the direction of length of the belt, such pattern is of a length equal to only a fraction of the length of the belt, yet, due to the manner of placement of said markings relative to the expanse of the pattern, said markings may serve as fully dependable and always clearly understood guides for the punching of said holes and also for the easy establishment of said slot.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a collective view, showing, in plan, such a plurality of the patterns of the invention as is now favored to be included in the kit (with all these patterns drawn to about one-half full scale), and also showing, in perspective, and drawn to about full scale, the round hole punching die also to be included in the kit.

Fig. 2, drawn to about twice full scale, is a section through said punching die, taken on the line 2—2 of Fig. 1.

Fig. 3 is an elevational view of said die, looking toward the right in Fig. 2.

2

Fig. 4 is a perspective view, showing one of the patterns of Fig. 1, placed on a belt near the tongue end of the latter, as for conducting one step of the method.

5 Fig. 5 is a view similar to Fig. 4, but showing the last-named pattern, after completion of the last-named method step, now placed on the same belt but at the end of the latter opposite its tongue end, as for conducting another step of the method.

10 Fig. 6 is a fragmentary view in perspective, showing use of the die by hammer tap thereagainst.

15 Fig. 7 is a perspective view showing a book construction wherein each of a plurality of patterns to be included in the kit is carried by a different transparent sheet, with these sheets padded together.

20 Fig. 8 is a perspective view, showing the two lower of said sheets swung out of the way and there temporarily interlocked, to permit use pursuant to the invention of the uppermost sheet of the pad.

25 Fig. 9 is a similar view, but with now the top and bottom sheets swung out of the way and there temporarily interlocked, to permit use pursuant to the invention of the middle sheet of the pad.

30 Fig. 10 is a view similar to Figs. 8 and 9, but with now the two upper sheets swung out of the way and there temporarily interlocked, to permit use pursuant to the invention of the lowermost sheet of the pad.

35 Referring to the drawings more in detail, and first to Figs. 1 through 6, the plurality of patterns to be included in the kit are indicated as three in number; these patterns, respectively designated 15, 16 and 17, being exactly alike, except that the pattern 16 is wider than the pattern 15, and the pattern 17 is wider than the pattern 16.

40 These patterns desirably are made of a fairly heavy paper or of an exceedingly thin and flexible cardboard suggestive of heavy manila wrapping paper.

45 Each pattern has like apertures; these including a plurality of round holes 18, herein shown as five thereof, equally spaced longitudinally of the pattern. These holes 18, as a group, are closer to one end of the pattern than to the other. The 50 end of the pattern to which said group of holes is closer is desirably pointed as indicated at 19 on the pattern 15.

Each pattern, further, and near its end opposite to its pointed or tongue end 19, is further apertured as at 20; this aperture 20 being a slot elongated in the direction of length of the pat-

tern, for being used as a guide to assist in providing, at the buckle end of the belt, a slot through the belt for accommodation of the prong of a buckle on the belt.

A belt is fragmentarily illustrated at 21. As said belt is herein shown, it is of the same width as the pattern 15, and consequently the pattern 15 will be used in connection with that belt, while employing the round hole punching die, 22, included in the kit.

Said punching die 22, as best shown in Figs. 2 and 3, is in the main cylindrical; but tapered toward one end which is hollowed out to provide a circular cutting edge 23 above which, inside the die, is an upwardly extending throat 24 terminating in a discharge opening 25 for the small disk-like pieces of material cut from the belt material incidental to the aperturing of the belt by use of the die 22, as by hammer tap thereagainst, as indicated in Fig. 6.

The pattern 15 will be used not only in connection with a belt which like the belt 21 is of the same width as the pattern 15 but also in connection with a belt which while wider than said pattern 15 is less wide than the pattern 16. Similarly, the pattern 16 will be used not only with a belt which is of the same width as the pattern 16 but also in connection with a belt which while wider than said pattern 16 is less wide than the pattern 17. Likewise, the pattern 17 will be used with a belt which is as wide as or wider than the said pattern 17. In all cases, therefore, it will be a simple and easy matter to arrange the longitudinal center line of the pattern with the longitudinal center line of the underlying belt. Thus one of merely three patterns may be used as guides for any one of a multiplicity of belts of slightly varying widths between a wide range of different widths.

With a pattern arranged relative to a belt as is the pattern 15 relative to the belt 21 in Fig. 4, the pattern and belt are in registry at the tongue ends of both, and now the locations of the holes 18 mark off the proper locations for corresponding holes through the belt. Consequently, use of the die 22 as already explained, at each of the different holes 18, seriatim, results in establishing corresponding holes along the tongue end of the belt as partially indicated at 26 in Fig. 5.

With the belt of leather, imitation leather, plastic or some non-ravellable sheet material, the punching of such holes 26 therethrough is all that is required; whereas if the belt be of cloth or has a cloth cover or facing, the holes 26 may be easily and conveniently finished off by the ordinary buttonhole stitching.

Where the end 27 of the belt opposite to its tongue end is to be provided with a slot for accommodating the prong of a buckle, the same pattern 15 (or 16 or 17, as the case may be) which was used or is to be used for aperturing the belt in accordance with the number and placement of the round holes 18 through said pattern, is also used to make it possible to establish said slot through the belt quickly, easily and at precisely the correct location—by guidance of the slot 20 as already stated. All that is required is to slip the pattern along the length of the belt until the end of the pattern which is adjacent to the slot 20 is lined up with the buckle end 27 of the belt; and then to use the punch 22, as shown in Fig. 6 and as already explained, but merely once at each of the two ends of said slot 20.

Following removal of the pattern, a sharp knife or even a small pair of scissors may be used for

the making of a pair of parallel straight-line slits through the belt material thereby to transform the two punchings last referred to into the desired slot through the belt.

With the belt of leather, imitation leather, plastic or some analogous sheet material, the establishment of said slot through the belt as just explained is all that is necessary; whereas if the belt be of cloth or has a cloth cover or facing, 10 said slot may be easily and conveniently finished off by the ordinary buttonhole stitching.

In accordance with the invention, the patterns 15, 16 and 17 are applied to the sheets of a book wherein a single selected sheet may be exposed 15 to view, the remaining sheets being held together to help maintain the book open to expose the desired pattern.

As shown in Figs. 7-10, each pattern 15', 16' and 17', these respectively corresponding to the 20 patterns 15, 16 and 17, is carried, so far as its outline is concerned, as a printing on a different one of three transparent sheets A, B and C all alike. Each of these patterns, at appropriate points within the expanse thereof, is apertured, 25 as shown, in accordance with the described aperturing of each of the patterns 15, 16 and 17 to provide the round holes 18 and the slot 20 thereof.

The sheets A, B and C are suitably padded 30 together, as by use of wire staples as indicated at 28. As a consequence, there is no necessity to fumble for a desired pattern, and also no chance to lose or mislay any pattern.

Nevertheless, the pattern on any sheet A, B or 35 C, may be used, without detaching that sheet from the pad; yet without interference from the other two sheets of the pad. In other words, means are provided for quick and quick-releasable yet dependably adequate interlocking of any two sheets of the pad other than that sheet the pattern of which is desired to be used, while said two sheets are swung out of the way. Each sheet A, B and C, it will be noted, has, at its end remote from the staples 28, a tab 29, and a slit 30, parallel to the base of the tab and spaced inward from such base. Thus, when it is the pattern 15' on the sheet A which is to be used, the parts are arranged as in Fig. 8; with the tab 29 of the sheet B now sent through the slit 30 of the sheet C. Similarly, when it is the pattern 16' on the sheet B which is to be used, the parts are arranged as in Fig. 9; with the tab 29 of the sheet C now sent through the slit 30 of the sheet A. Likewise, when it is the pattern 17' on the sheet C which is to be used, the parts are arranged as in Fig. 10; with the tab 29 of the sheet B now sent through the slit 30 of the sheet A.

While I have illustrated and described the preferred embodiment of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A book for carrying a plurality of patterns comprising a plurality of superimposed sheets, each sheet carrying a pattern, means securing said sheets together at one end thereof, a slit in each sheet adjacent the other free end, and a tab on each sheet extended from the free end of said 70 sheet adjacent the slit, the tabs and slits being

adapted to interlock when selected sheets are bent back, thereby exposing a single sheet to use.

SALVATORE GUGGINO.
